UNITED STATES PATENT OFFICE.

AARON J. YARLOT AND GEORGE B. M. YARLOT, OF NEY, OHIO.

FENCE.

SPECIFICATION forming part of Letters Patent No. 341,120, dated May 4, 1886.

Application filed October 21, 1885. Serial No. 180,530. (No model.)

To all whom it may concern:

Be it known that we, AARON J. YARLOT and GEORGE B. M. YARLOT, citizens of the United States, residing at Ney, in the county 5 of Defiance and State of Ohio, have invented certain new and useful Improvements in Fences; and we do hereby declare the following to be a full, clear, and exact description of the invention, such as will enable others 10 skilled in the art to which it appertains to make and use the same.

Our invention relates to fences, and has for its object to make a fence which will be simple and strong, and capable of being easily and 15 readily taken down and set up, and also moved from place to place, as may be desired; and to those ends the invention consists in the construction and combination of parts hereinafter particularly described and claimed, reference 20 being had to the accompanying drawings, forming a part hereof, and in which—

Figure 1 is a perspective of one section of a fence, with portions of two other sections, showing the manner of forming and putting 25 the same together. Fig. 2 is a cross-section through the lower portions of the posts where two sections join. Fig. 3 is an end view of a modification.

In the drawings, the letter A designates a 30 cross-sill to rest upon the ground, and B a secondary or auxiliary sill, preferably of shorter length than A, and placed at such a distance from the latter as to leave a space between the two for the reception of the lower ends of the 35 two posts C and D. A block or stop, E, is placed between the two sills, so as to close the space at one end and form a bearing to assist in holding one of the posts, which will be removable in place. The posts are set in the 40 space between the sills, far enough apart to leave a space between the posts for the passage of the rails F, which fit in said space, one upon the other, and are held in place by the posts. The post C is held in place and stationary by 45 means of a brace-wire, G, passed through two holes, a and b, in the post, as shown, although this feature is not claimed in itself, and having its ends connected to opposite ends of the

cross-sill A. This wire, when the fence is up and the two posts connected together at their 50 upper end by wire H, would be sufficient to brace and secure the stationary post; but in addition thereto the lower end of the post may be secured by nails or fastenings I, passed through both sills and the rail. Where the 55 rails come in contact with the brace-wires, they are formed with a slot, c, so that the wires will enter the same and pass through from one side to the other of the rails. In this way the rails can be removed without disturbing the wires. 60 The post D fits the space between the sills without being fastened thereto or to any other part of the fence except to the post C by the wire H, so that by simply removing the wire H the post can be lifted out of place and the 65 other post, C, together with the cross-sills and connecting-block, can be removed intact, so as to be set up again at any desired point. This construction permits the fence to be constructed at comparatively little cost, and forms 70 a fence that is easily portable and can be set up and taken down by the most unskilled labor and at the minimum loss of time.

Obviously changes in the construction and arrangement of parts can be made without departing from the spirit of my invention.

When a board fence is made, the posts C and D, one or both, may be formed with recesses d on their inside or meeting faces, as shown in Fig. 3, so that the boards can rest in 80 the recesses, and thus be supported, instead of one board resting upon the other. The recesses may be opposite to each other or arranged in the order shown in Fig. 3. It is obvious, too, that there may be a post between the two end 85 posts, so as to strengthen the rails or boards, if necessary.

Having fully described the invention and set forth its merits, what we claim is—

1. The fence composed of the cross-sill A, 90 the auxiliary sill B, the stop E between the sills, the removable post D, the stationary post C, the rails F, having their ends fitting between said posts, wires H around the upper ends of the posts, and wire G, passed 95 through the stationary post and through an

opening in one of the rails, and secured at its ends to the opposite ends of the cross-sill A, substantially as described.

2. The combination of the posts, the cross-sill, the wire connecting one of said posts and cross-sill, and the rails fitting between the posts, one of said rails being formed with a slot for the passage of the wire to permit the removal of the post without disturbing the wire, substantially as described.

In testimony whereof we affix our signatures in presence of two witnesses.

AARON J. YARLOT.
GEORGE B. M. YARLOT.

Witnesses:

REUBEN L. STARR,
